CLAIM

The ornamental design for a playing board for a board game, as shown and described.

DESCRIPTION

In an embodiment, as shown in FIG. 9, the playing board for a board game can be coupled with a supporting board. The supporting board may be (i) another playing board which may be the same as or different from the playing board for a board game of the present invention, (ii) a mere support which does not serve for a board game, or (iii) a tray to provide a storage space for moving pieces when the moving pieces are not in use.

Moving pieces can be stored in a ditch of the playing board when in use. When not in use, moving pieces can be stored inside a space which is defined by the playing board for a board game and the supporting board.

FIG. 1 is a top perspective view of a playing board for a board game showing my new design.

FIG. 2 is a bottom perspective view thereof.

FIG. 3 is a top view thereof.

FIG. 4 is a bottom view thereof.

FIG. 5 is a left side view thereof.

FIG. 6 is a right side view thereof.

FIG. 7 is a front side view thereof.

FIG. 8 is a rear side view thereof.

FIG. 9 is a perspective view of the playing board of FIG. 1, shown in conjunction with an exemplary supporting board; and

FIG. 10 is a perspective view of a second embodiment of the Playing Board for a Board Game wherein game playing chips are included.

The broken lines are provided for illustrative purposes only and form no part of the claimed design.
